C. W. N. Smith

United States Patent Office.

JOHN H. MOONEY, OF SAN FRANCISCO, CALIFORNIA.

Letters Patent No. 97,544, dated December 7, 1869.

IMPROVEMENT IN TUCK-CREASER FOR SEWING-MACHINE.

The Schedule referred to in these Letters Patent and making part of the same.

To all whom it may concern:

Be it known that I, JOHN H. MOONEY, of the city and county of San Francisco, State of California, have invented certain new and useful Improvements in Tuck-Markers; and I do hereby declare the following description and accompanying drawings are sufficient to enable any person skilled in the art or science to which it most nearly appertains, to make and use my said invention or improvements without further invention or experiment.

The nature of my invention consists of a device for simply marking or creasing the tuck, so arranged that it will be noiseless, and easily adjusted. The tension or force of the tuck-bar may be regulated for thick or thin fabrics, without accelerating or retarding the travel of the cloth beyond the ordinary speed imparted by the presser-foot of the sewing-machine. A second tuck may be creased while the previous one is being stitched.

Referring to the accompanying drawings—

Figure 1 represents a side elevation, showing the position of the striking-arm under the needle-arm of a sewing-machine.

Figure 2 is a plan of tuck-marker.

The plate A, which carries the mechanism, rests upon the needle-plate of the sewing-machine, and is kept in position by a vertical bar, B, passing through a slot in the table.

The upper end of the plate is turned, to provide a swivel, or hinge, for the striking-arm C, the ends of which are curved at nearly right angles in opposite directions, one end entering the swivel, and the opposite angle is provided with a friction-roller, D, which is operated by the bar C, which is in turn operated by the needle-arm.

Near the lower curve of the arm C is also placed a friction-roller, D', which operates upon the conical cam at the end of the tuck-bar.

The tuck-bar, or creasing-arm, is bent at right angles, and one end carries the conical cam E, and the

opposite end the creaser F, which is provided simply with a longitudinal groove. This bar works in a journal at one side of the plate.

When the needle-arm plays upon the friction-roller D at the end of the arm C, the roller D' plays along the conical cam or roller E, which causes the creaser to impinge upon the cloth to form the crease.

The spiral-spring F², around the bar, throws it back when relieved by the needle-arm.

The force of the blow, or weight of the creaser, is regulated by moving the conical cam on the thread at the end of the tuck-bar, thereby lengthening or shortening the stroke of the needle-arm upon the roller D.

The face of the base-plate is marked 1, 2, 3, indicating inches, which are subdivided into smaller spaces; and the width of the tuck is regulated by adjusting the base-plate under the slotted holding-plate, which is held in place by a set-screw, and is grooved to receive the rod H, which acts as a guide for the base-plate. The holding-plate may also assist in holding down the plate on the table.

Having thus described my invention, what I claim, and desire to secure by Letters Patent, is—

1. The arm C, having thereon friction-rollers D D', and operated by the needle-arm in combination with the conical cam E, substantially as described.
2. The adjustable conical cam, in combination with the creasing-arm for regulating the force of the arm on the fabric, to form the crease, as desired.
3. The combination, with the arm C, and the rocking creasing-bar F, of the base-plate A, slotted holding-plate G, and rod H, when all are constructed and combined as and for the purpose set forth.

In testimony whereof, I have hereunto set my hand and seal.

JOHN H. MOONEY. [L. S.]
